DESIGN FOR A PORTABLE CONCRETE MIXER

Harold A. Wagner and Gustave H. Wagner,
Portland, Oreg.

Application January 11, 1943, Serial No. 109,230

Term of patent 14 years

To all whom it may concern:

Be it known that we, Harold A. Wagner and Gustave H. Wagner, citizens of the United States, residing at Portland, in the county of Multnomah, State of Oregon, have invented a new, original, and ornamental Design for a Portable Concrete Mixer, of which the following is a specification, reference being had to the accompanying drawings, forming a part thereof.

In the drawings, Fig. 1 is a side elevational

view of a portable concrete mixer showing our new design, Fig. 2 is a front elevational view, Fig. 3 is an end elevational view, Fig. 4 is a top plan view and Fig. 5 is a front elevational view with the loading skip removed.

We claim:

The ornamental design of a portable concrete mixer, substantially as shown.

HAROLD A. WAGNER.
